UNITED STATES PATENT OFFICE.

RICHARD BORGFELDT, OF METUCHEN, NEW JERSEY, ASSIGNOR OF ONE-HALF TO
HERBERT G. LATIMER, OF BROOKLYN, NEW YORK.

COMMUTATION-TICKET.

1,159,642.

Specification of Letters Patent.

Patented Nov. 9, 1915.

Application filed September 24, 1914. Serial No. 863,319.

To all whom it may concern:

Be it known that I, RICHARD BORGFELDT, a citizen of the United States of America, and residing at Metuchen, in the county of 5 Middlesex and State of New Jersey, have invented a certain new and useful Improvement in Commutation-Tickets, of which the following is a specification.

My invention relates to commutation 10 tickets and the object of my invention is to provide a railroad ticket of this type which will prevent certain abuses to which the use of tickets of this character has commonly been subject.

15 In the accompanying drawings, Figures 1 and 2 are plan views of commutation tickets in which my invention is embodied in different forms; and Fig. 3 is a diagrammatic plan of a railroad.

20 Commutation tickets as now commonly printed bear punch boxes consecutively numbered and entitling the holder thereof to continuous rides in either direction between the points named on the ticket. One of the 25 express conditions of a commutation ticket is that it shall be used for a continuous ride between the points specified thereon, except in the event that the train boarded by the owner of the ticket does not travel the 30 full distance called for by the ticket, in which event the holder of the ticket is entitled to complete the journey by boarding the next connecting train. It has been the common practice of the railroads however 35 to issue commutation tickets on which the size of the punch boxes is so small that they will accommodate but a single punch to the box, and the conductor is instructed to punch a box immediately the train leaves the 40 terminus A or C between which the ticket is issued. As a result of this practice, a degree of uncertainty and looseness of requirements has crept in, which has become the occasion of various abuses of the 45 commutation ticket and results in serious losses to the railroads. Perhaps the most serious loss is occasioned by the use of commutation tickets by drummers having business at various stations along the line. Such a drummer 50 boarding an accommodation train say at A, has his ticket punched and gets off at the first station 1. After doing an hour's business here, he boards the next accommodation train and rides to station 2, later to 3, and so on. When approached

by the conductor after boarding the train, say at station 2, he states that he possesses a commutation ticket which has already been punched, and the conductor is commonly satisfied with this. If the conductor however demands inspection of the ticket and discovers that the alleged punch is not his own, he commonly punches another box. The conductor has however permitted the use of the ticket not only for travel initiated at a way station but also for travel between way stations, both of which uses are outside the conditions of the contract under which the ticket is sold. Again, since the punch box bears no indication of 60 the direction in which the journey is initiated, it is possible to travel say from A to B, where the train stops. It is possible to return later to A from B on a train starting 65 at B and connecting with a train from C which stops at B and with which it is destined to make connection. If the ticket is presented, unscrupulously, as a continuation of a journey initiated at C, it enables the user to travel back from B to A on the same 70 punch box as that on which he traveled earlier in the day from A to B. As has been stated however, a commutation ticket is issued, and at a reduced rate, only for a continuous ride between the points specified. 75 It can not properly be presented for a stage by stage journey between the stations named, and in fact cannot properly be presented 80 for transportation on a trip initiated at an intermediate point. Obviously it cannot 85 properly be presented for a journey both to and from an intermediate station.

To remedy the abuses noted and other misuses of the ticket, I now provide a commutation ticket with punch boxes of sufficient size to permit the conductor of a connecting train (as from B to C) to punch in the same box with the conductor of the train boarded for the first portion of the journey from A to B. I also print in the punch 95 boxes insignia to indicate the direction of travel in which the journey is initiated. Furthermore, each punch box is provided with a serial number.

The tickets shown in the accompanying 105 drawing embody my invention in two forms. Thus the ticket of Fig. 1, has at its head, the usual space 5 for the name of the issuing railroad, the points for travel between which the ticket is issued, and the period during 110

which it is to be accepted; the box 6 for the dating stamp and the box 7 for the notice that the ticket is subject to the terms of contract printed on the back; while the 5 large area on the lower portion of the ticket is divided into a series of punch boxes 8 for cancellation by the conductor. Each of these punch boxes is sufficiently large to accommodate two punches and in each box above and below its numeral 9 are printed 10 insignia 10 such as the letters E. and W. or N. and S. to indicate the direction of travel.

If the commuter boards at A a train which travels through to C, even though it 15 makes intermediate stops, the conductor will at once punch its numeral 9, thereby denoting that the box is exhausted since the holder has had the opportunity for the through travel between A and C for which 20 the ticket is issued. It cannot be offered at 1, 2 or B for a continuation of a journey unwarrantably interrupted by the holder of the ticket.

If the commuter boards a train going only 25 as far as B, the conductor punches one of the insignia 10 to indicate the direction in which the journey is initiated *e. g.*, east. Obviously it will not be accepted by the conductor of another train for a return journey 30 west from B, since this box is good only for a completion of the journey already initiated in the opposite direction.

In each of the above cases the second conductor is entitled to collect fare from the 35 holder of the ticket, from the point at which the train is boarded to the destination, since the ticket is issued only for a continuous journey between the points mentioned in the ticket. The passenger is not entitled at any 40 time to board the train at an intermediate station and present the ticket for a ride from such station—say from 2 to C. The ticket must be presented at A for a continuous ride to C; or at C for a continuous ride 45 to A, with the sole exception of trains going no farther than B, and in such case only on the next connecting train. If the conductor of the connecting train at B is familiar with the punch of the conductor of the preceding 50 train stopping at B, he can readily observe whether or not the passenger who presents for further travel a partially punched box, has traveled on the next preceding train or on some earlier train and should have gone 55 forward by an earlier connecting train. If the latter is the case, the conductor is entitled to collect fare from the passenger.

It will be clear from the foregoing that 60 the practice of drummers heretofore mentioned of journeying by stages between the points specified in the ticket is readily checked by the use of a ticket of the character described, since the presentation of a ticket having its serial number punched indicates that the journey has been begun on a

through train and the stop-over was unwarranted, while the presentation of a ticket punched at 10 indicates its exhaustion to the point B. Furthermore, the constant rule prevails that a ticket from A to C is never 70 good from an intermediate station (*e. g.* 1, 2, 3, etc.) except it be a terminus such as B and then only on the next connecting train.

The ticket shown in Fig. 2 has the advantage over that shown in Fig. 1 in that 75 whereas the latter has its punch boxes arranged in a single series of sixty, as is the usual form for a monthly ticket, the form shown in Fig. 2 has the boxes arranged in a double series of thirty each, corresponding 80 to the days of the month, and preferably symmetrically arranged with relation to each other. Each box has a direction indication, but in a single direction only. Consequently the conductor may punch only that box 85 which corresponds to the day of the month on which the trip is made and will punch one box for the journey in one direction, and the other box for the journey in the opposite direction. For a journey initiated on a train 90 going only as far as B from either A or C, the conductor punches in the appropriate box the insignia 10 designating the direction of travel, and the ticket can obviously be presented for continued travel only on the 95 same date on which it is initiated since the punch box in question shows its use on that date. It is one of the privileges attaching to a commutation ticket, however, that the holder may ride more than once in a single 100 day between the points specified in the ticket. To provide for this contingency, the ticket may have two or more of its rows of boxes provided with stars 11, one of the rows for travel in one direction and one for travel in 105 the opposite direction. In case the commuter has exhausted the boxes designated for the date in question, say, box 2; but again wishes to make the round trip on that date, the conductor now punches in one of 110 the boxes containing the star 11. By punching the star he indicates that there has been no ride on the date to which the canceled star box corresponds, but that the ride has been taken on some other date as an extra on 115 that date. Consequently, on the date of the canceled star box he may punch any box on the ticket which remains uncanceled.

The particular forms of ticket may be varied in accordance with the particular demands of the railroad using the same, and that shown is merely an exemplification of my invention. Thus the invention may be applied to a family ticket of the fifty, twenty-five or ten ride type and in the following claims the expression "commutation ticket" is used in a sense broad enough to cover this type of ticket also. By reason of the higher rate at which it is sold, the family ticket is privileged for travel between way 120 125 130

stations—a new punch box being canceled each time the train is boarded. The railroad loses nothing by this, since the price of the ticket is such that the value of each 5 punch box is greater than the ordinary fare between any of the way stations. By reason of the fact however, that each punch box contains a direction indication it will be impossible for the holder of a ticket of this 10 type to ride say from A to B, and after doing business return from B to A on the same punch box, as is now frequent practice. The conductor on the train from A to B punches the direction indicia 10, so that 15 the conductor of the later return train from B to A sees at a glance that the journey was initiated in the opposite direction and consequently punches an additional punch box.

I claim as my invention:—

20 1. A commutation ticket having a series of punch boxes thereon, said ticket having printed matter entitling the owner to continuous rides between specified points, and said punch boxes having travel-direction in-

dicia thereon and being consecutively numbered and of sufficient size to receive a plurality of punches by the conductors of connecting trains. 25

2. A commutation ticket having a series of punch boxes thereon, said ticket having 30 printed matter entitling the owner to continuous rides between specified points, each of said punch boxes having a numeral adapted to be punched by the conductor of a through train and each punch box having, 35 also, direction indication adapted to be punched by the conductor of a way train, said boxes being of sufficient size to receive a plurality of punches, substantially as described. 40

In testimony whereof I have signed my name to this specification, in the presence of two subscribing witnesses.

RICHARD BORGFELDT.
